United States Patent Office

Des. 225,903

Patented Jan. 9, 1973

225,903

FILM INSPECTION MACHINE

Ray L. Short, Jr., Glenview, Ill., assignor to Research Technology Incorporated, Skokie, Ill.

Filed July 16, 1971, Ser. No. 163,553

Term of patent 14 years

Int. Cl. D16—99

U.S. Cl. D61—1

Fig. 1

Fig. 2

Fig. 3

FIG. 1 is a front perspective view of a film inspection machine showing my new design;

FIG. 2 is a right side elevational view, the left side being a mirror image thereof;

FIG. 3 is a rear elevational view thereof.

I claim:

The ornamental design for a film inspection machine, as shown and described.
